UNITED STATES PATENT OFFICE.

BEVIER VAN GORDER, OF NEW YORK, N. Y., ASSIGNOR TO WESER BROS., INC., OF NEW YORK, N. Y., A CORPORATION OF NEW YORK.

MECHANICAL MUSICAL INSTRUMENT.

Application filed March 3, 1924. Serial No. 696,461.

My invention relates generally to pneumatically operated musical instruments, such as player-pianos, organs and other similar instruments in which a perforated music sheet travels over a tracker-bar and in which power for operating the various mechanical parts is derived from the main wind-chest placed under exhaust pressure.

My invention is particularly concerned with an improved attachment by which various changes in expression may be more readily controlled, either directly or indirectly, by means of an improved automatic attachment embodied in the customary main reservoir bellows. In certain types of mechanical musical instruments operated by exhaust or vacuum pressure, such air tension has been produced by a combination of foot-operated pumping bellows and an electric motor directly rotating an exhaust fan or with feeder-bellows actuated by the motor, in which the action of the foot-operated pumping bellows is independent of the motor exhaust, though both are directly connected with the main player action wind-chest so that the foot-operated pumping bellows may be utilized as an expression device.

The aim of my invention is, among other things, to provide a simplified yet effective automatic attachment mounted within the usual main reservoir bellows whereby such main reservoir bellows may be entirely cut off from the usual exhaust connections while the motor-operated exhaust devices are in operation and connected to the player action pneumatics through the wind chest, though allowing such main reservoir bellows to be automatically connected with the wind chest when the full effect of a powerful action of the pumping bellows is used in accenting certain notes or performing fortissimo passages when the motor-operated exhaust devices are not in operative connection with the player action through the wind chest.

With the foregoing and other objects in view, the invention comprises the various features of construction and combination of parts and the mode of operation here-

inafter described and particularly pointed out in the appended claims.

In the drawings, Fig. 1 is a front elevation of a player-piano with parts broken away and the front casing removed showing 55 an embodiment of my invention in somewhat diagrammatic form in connection with reproducing devices regulated by the music-sheet in conjunction with suitable ports in the tracker-bar; 60

Fig. 2 is a sectional view of my improved attachment taken on the line 2—2 of Fig. 3 looking in the direction of the arrow;

Fig. 3 is a top plan view of such attachment; and 65

Fig. 4 is a sectional view taken on the line 4—4 of Fig. 1 looking in the direction of the arrow.

Similar numerals refer to similar parts throughout the several figures. 70

Referring to the drawings, more particularly to Fig. 1, the player-piano chosen for a preferred embodiment of the invention comprises the case 5 with the tracker-bar 6 having the pneumatic control openings 7 75 (four being shown in Fig. 1) each connected by separate tubes 8 with the customary primary valve box 9 mounted on the reproducer box 10 fastened to the inner side of the case 5 as shown. The electric motor 11 operating 80 an exhaust fan or bellows is secured within the case 5 as shown in Fig. 1, and the pipe 12 connects the motor exhaust devices with the main player action wind-chest 13 which is connected through the port 14^a to 85 the gate-box 14 which is also connected through the port 23 to the main reservoir bellows 15 having the reserve reservoir bellows 16 connected thereto as shown in Fig. 1.

The main reservoir bellows 15 has connected therewith the auxiliary pneumatic 15^a as shown in Figs. 1 and 4. The wind chest 13 is also connected to the pumping bellows 17 by valved connections 17^a and is operated, as usual, by the pedals 18. 95 One end of the gate box 14 is connected by the pipe 19 with the wind motors (not shown), and from the opposite end of the gate box 14 the pipe 20 extends by the conduit 44 to the player action-chest 45 for the 100

usual hammer pneumatics 46 comprised in the player-action. The pipe 21 connects the reproducer box 10 with the pipe 20 to vary the air tension in the action chest in the usual manner. The tempo valve seat 47 having the graduated port 48 to regulate the speed of the wind-motor (not shown) is fragmentarily illustrated in Fig. 4.

All of these parts thus far referred to are constructed and operated in the usual manner and need not be further described as they do not constitute in themselves the present improvements, but are part of the usual player-piano construction.

Referring more particularly to Figs. 2, 3 and 4, the front panel 22 of the main reservoir bellows 15 is connected, as usual with the player action wind chest 13 by port 23, which port is opened and closed by the following devices: To the inner face of the panel 22 a block 24 is fastened by screws 25 and spaced from the block 24 is the swinging valve 26 adapted to close the port 23 when the valve 26 is forced against the face of the panel 22. Suitably secured to the under side of the valve 26 is the washer 27 formed of felt or other suitable material to enable the valve 26 to have a tight fit over the port 23; the washer 27 preferably extends under the block 24 as shown in Figs. 2 and 4 to form the necessary hinge for the valve 26. The lower end of the valve 26 is slotted at 28 within which slot is the guide pin 29. The valve 26 is normally maintained in raised or open position as shown in Figs. 2 and 4 by the leaf spring 30 fulcruming on the block 24 with one end fastened to the block 24 by screw 31 while the other end is secured to the valve 26 by screw 32 as shown in Figs. 2 and 3. The valve 26 has the bleed passage 33 to the port 23 which passage is normally opened but is closed by the valve 34 fastened to the under side of the spring arm 35 secured by screws 36 to the top of the valve 26. The end 37 of the spring arm 35 is adapted to be pressed down by the felt button 38 carried on the outer end of the arm 39 mounted on the movable leaf 40 of the control pneumatic 41 secured to the panel 22 adjacent the lower end of the valve 26. The leaf 40 is normally held in the raised position shown in Figs. 2 and 4 by the usual spring (not shown). The nipple 42 extends from the inside of the pneumatic 41 through the panel 22 to the pipe 43 which is connected to the pipe 12 as shown in Fig. 1.

The operation of my improved attachment is substantially as follows: When the wind-chest 13 is under exhaust pressure from the electric motor exhaust devices 11, the pneumatic 41 is held in collapsed position through the pipe 43 connection, and the button 38 presses down on the end 37 of the spring arm 35. This downward movement

of the button 38 simultaneously closes the port 23 and the bleed passage 33 by the valves 26 and 34 respectively, thereby effectively cutting off the main reservoir bellows 15 from the wind chest 13. Thereupon the wind-chest 13 is directly connected with the action pneumatics 46 through the pipe 20. The valves 26 and 34 remain in their closing position as long as the wind chest 13 is under exhaust pressure from the motor 11 so as to enable the selective control openings 7 in the tracker to regulate the varying degrees of air tension on the action pneumatics 46 through the reproducer box 10 without drawing air from the main reservoir bellows 15. This attachment, it will be observed, enables the expression to be better and more readily controlled while the motor operated exhaust devices are connected with the player action.

When the motor exhaust is cut off from the pipe 12 leading to the wind-chest 13, the spring tensioned leaf 40 immediately raises and the valve 26 opens the port 23 to connect the main reservoir bellows 15 with the player action with chest 13, whereby certain notes or passages may be accented through the action of the pumping bellows 17 when the motor exhaust devices 11 are cut off therefrom by mechanism that need not be here described.

The foregoing construction shows a practical form of attachment embodying the essential principles of my invention, but various changes may be made in the structural details and arrangement of the parts without departing from the scope of my improvements and without sacrificing its chief advantages.

I claim as my invention:

1. In a pneumatically-operated musical instrument, a main reservoir bellows, a wind-chest normally connected therewith, means for exhausting said reservoir bellows, a normally open valve controlling communication between said reservoir bellows and said wind-chest, and means actuated by said exhausting means for closing said valve to completely cut off said main reservoir bellows from the wind-chest.

2. In a pneumatically-operated musical instrument, a main reservoir bellows, a wind-chest normally connected therewith, a motor-operated exhaust device connected with said reservoir bellows, a normally open valve controlling communication between said reservoir bellows and said wind-chest, and means actuated by said exhausting device for closing said valve to completely cut off said main reservoir bellows from the wind-chest.

3. In a pneumatically operated musical instrument having a main reservoir bellows, a player action wind-chest in operative connection therewith, a motor-operated exhaust

device indirectly connected with said main reservoir bellows, and means for completely cutting off said main reservoir bellows from the action wind-chest while allowing said 5 action wind-chest to be connected with said exhaust device.

4. In a pneumatically operated musical instrument having a main reservoir bellows, a player action wind-chest in operative 10 connection therewith, a motor-operated exhaust device indirectly connected with said main reservoir bellows, and means for completely cutting off said main reservoir bellows from the action wind-chest, and connecting 15 said action wind-chest with said exhaust device.

5. In a pneumatically operated musical instrument having a main reservoir bellows, a player action wind-chest in operative 20 connection therewith, a motor-operated exhaust device indirectly connected with said main reservoir bellows, and means for cutting off said main reservoir bellows from the action wind-chest and connecting said action wind-chest with said exhaust device actuated by 25 the pressure in said exhaust device.

6. In a pneumatically operated musical instrument having a main reservoir bellows, a player action wind-chest in operative 30 connection therewith, a motor-operated exhaust device indirectly connected with said main reservoir bellows, and means for completely cutting off said main reservoir bellows from the action wind-chest while allowing said 35 action wind-chest to be connected with said exhaust device controlled and actuated by the varying pressure in said exhaust device.

7. In a pneumatically operated musical 40 instrument having a main reservoir bellows, a player action wind-chest, a motor-operated exhaust device connected with said main reservoir bellows, an air-port between said main reservoir bellows and action wind-chest with a normally open valve to close same, and a pneumatic controlled and actuated by 45 said exhaust device to operate said valve to completely close said air port.

8. In a pneumatically operated musical 50 instrument having a main reservoir bellows, a player action wind-chest, a motor operated exhaust device connected with said main reservoir bellows, an air-port between said main reservoir bellows and action wind-chest with a normally open valve to close same, a pneumatic to actuate said valve, and 55 connections between said exhaust device and pneumatic whereby said valve closes said port completely while said exhaust device is in operation.

9. In a pneumatically operated musical 60 instrument having a main reservoir bellows, a player action wind-chest in operative connection with said main reservoir bellows, a motor-operated exhaust device connected 65 with said action wind-chest, foot-operated

pumping bellows also connected with said action wind-chest, and means actuated by said motor exhaust device for automatically and completely cutting off said main reservoir bellows from the action wind-chest. 70

10. In a pneumatically operated musical instrument having a main reservoir bellows, a player action wind-chest in operative connection with said main bellows, a motor-operated exhaust device connected with said 75 action wind-chest, foot operated pumping bellows also connected with said action wind-chest, and means comprising a pneumatically controlled valve actuated by said motor exhaust device for cutting off said main reservoir bellows from the action wind-chest.

11. In a pneumatically operated musical instrument, a player-action wind-chest, a reservoir bellows connected therewith, a valve to control the tension produced by said 85 reservoir bellows in said action wind-chest, a bleed passage in said valve having a separate valve to close same, and a single means for closing both said valves by the tension in said reservoir bellows. 90

12. In a pneumatically operated musical instrument, a player-action wind-chest, a reservoir bellows connected therewith, a main valve to control the tension produced by said 95 reservoir bellows in said action wind-chest, a bleed passage in said valve having a separate valve to close same, and a single means for sequentially closing first said bleed-passage valve and then said main valve completely by the tension in said reservoir bellows. 100

13. In a pneumatically operated musical instrument controlled by a perforated music-sheet, a tracker-bar having pneumatic control openings, connections between said 105 openings and selective reproducing mechanism, a main wind-chest, a player action wind-chest, a main reservoir bellows connected with said main wind-chest, a motor-operated exhaust device connected with said main reservoir bellows, and means actuated by said exhaust device for cutting off said main reservoir bellows from the main wind-chest whereby said reproducing mechanism 110 may control the air tension in said player action wind-chest.

14. In a pneumatically operated musical instrument controlled by a perforated music-sheet, a tracker-bar having pneumatic control openings, connections between said 120 openings and selective reproducing mechanism, a main wind-chest, a player action wind-chest, a main reservoir bellows connected with said main wind-chest, a motor-operated exhaust device connected with said main reservoir bellows, and means comprising a pneumatically controlled valve actuated by said exhaust device for cutting off said main reservoir bellows from the main wind-chest whereby said reproducing mechanism may 125 130

control the air tension in said player action wind-chest.

15. In a pneumatically operated musical instrument controlled by a perforated music-sheet, a tracker-bar having pneumatic control openings, connections between said openings and selective reproducing mechanism, a main wind-chest, a player action wind-chest, a main reservoir bellows con-

nected with said action wind-chest, a motor-operated exhaust device connected with said main reservoir bellows, a pneumatically-actuated valve for cutting off said main reservoir bellows from the action wind-chest controlled by said exhaust device, and direct connections between said reproducing mechanism and said player action wind-chest. 10 15

BEVIER VAN GORDER.
